(57) **CLAIM**

The ornamental design for a pneumatic tire, as shown and described.

DESCRIPTION

FIG. 1 is a perspective view of a pneumatic tire showing my new design, it being understood that the tread pattern repeats throughout the entire outer circumference.

FIG. 2 is a rear elevation view thereof;

FIG. 3 is a front elevation view thereof;

FIG. 4 is a partial front elevation view thereof, shown at an enlarged scale;

FIG. 5 is a side elevation view thereof; and,

FIG. 6 is an opposite side elevation view thereof.

The broken lines in FIG. 4 show the boundaries of the figure only and form no part of the claimed design.
